Inventor:

A. W. Mahon.

UNITED STATES PATENT OFFICE.

AURELIUS W. MAHON, OF RICHMOND, VIRGINIA, ASSIGNOR OF ONE-HALF
TO CHAS. D. & HERBERT C. LARUS, OF SAME PLACE.

TOBACCO-PRESS.

SPECIFICATION forming part of Letters Patent No. 277,912, dated May 22, 1883.

Application filed February 8, 1883. (No model.)

To all whom it may concern:

Be it known that I, AURELIUS W. MAHON, a citizen of the United States, and a resident of the city of Richmond and State of Virginia, have invented a new and useful Improvement 5 in Machines for Pressing or Forming Lumps, "Nips," or Plugs of Tobacco, of which the following is a specification.

My invention relates to machines for forming or pressing lumps, nips, or plugs of tobacco from the loose fillers, preparatory to wrapping and repressing them; and my objects are to provide a machine which may be easily adjusted to any sized lump, that may be easily, 15 quickly, and certainly opened to remove the pressed lump and closed quickly and securely upon the loose tobacco to be pressed, a machine that will do its work quickly and accurately, pressing each lump to a uniform size 20 and density, and that is easily operated by workmen possessing little mechanical skill. I accomplish these important results by means of the mechanism hereinafter described, and illustrated in the drawings hereto annexed and 25 forming a part of this specification, in which—

Figure 1 is a side elevation, Fig. 2 a plan, and Fig. 3 an end elevation, of my machine.

Similar letters refer to like parts in the several views.

30 A A show an iron frame supporting the working parts, and upon which the steam-cylinder B is fixed. This cylinder contains a piston, M, the rod k of which passes through the stuffing-boxes b b of both heads, the machine being 35 double-acting, having pressing-boxes at each end. Upon each end of the piston-rod k are fixed the rams K K, to which are fixed the removable blocks or followers H H, which are exactly the size of the lump to be pressed, and 40 are changed for others whenever the machine is adjusted to another size of lumps. The blocks H H are loosely held to the rams K K by the hooks s s, fixed in the rams K K, and projecting downward through the followers or 45 blocks H H, as shown. The followers H H are inclosed by an adjustable iron box, consisting of the bed-plate T, the back plate, U, the sliding sides F F, and the pivoted apron or cover G. The sides F F slide in grooves planed 50 in the bed-plate T, and are opened and closed

by the crank N, upon whose shaft are the eccentrics n n, having their rods p p connected to the studs r r, which are fixed in slots in the sides F F by nuts, as shown. By this means a half-turn of the crank N opens or closes the two sides F F simultaneously, and holds them firmly in either position. When shorter or longer lumps are to be made, the studs r r are adjusted in the slots of the sides F F to correspond with the length of the lumps. In the 60 sides F F, at f, are a series of holes corresponding to the different widths of lumps to be made, and in any one of which the cover G is pivoted to suit the width of the lump when adjusting the machine. The cover G is 65 held down by the catch-lever g, upon which is a detent working into the catch g'. The catch g' is adjusted up or down by a bolt fitted to a slot in it and passing through the back plate, U. 70

Upon the piston M are the studs x x, which arrest the motion of the piston at either end always in exactly the same place.

Upon the piston-rod k are the adjusting-nuts w w, by means of which the rams K K are adjusted upon it, thus fixing the exact thickness 75 of the lump.

The supply of steam to the cylinder B is regulated by the valve D, which, together with the steam-passages, is identical with those of an ordinary "slide-valve" steam-engine, although the same result may be attained by the common "four-way cock" without materially altering my invention. The valve-stem m passes through the stuffing-boxes c c at each 80 end of the steam-chest E, and is pivoted at each end to the valve-levers d d. y is the steam-pipe leading from the boiler, and z is the exhaust-pipe. 85

The operation of my machine is as follows, 90 viz: The piston, valves, rams, &c., standing in the position shown in the drawings, the operator at the right-hand end of the machine throws up the pivoted cover G and fills the space C between the sides F F, follower H, and 95 back plate, U, with loose tobacco, closes the cover G, and fastens it with the catch-lever g. He then pulls the valve-lever d nearest him to the right, thereby forcing the valve D in the same direction. This admits steam to the left 100

end of the cylinder B, driving the piston to the right, and forcing the follower H upon the loose tobacco and pressing it to the required thickness. The valve-lever *d* remaining in this position, the pressure of steam holds the tobacco tightly until it "sets," while the operator at the left of the machine is filling his pressing-box. The valve-lever *d* being now thrown back to its position shown in the drawings, the lump at the left of the machine is pressed, while that at the right is released, and the operator at this end of the machine unfastens the catch-lever *g* and raises the cover G. He then, by a half-turn of the crank N, opens the sides F F, which completely releases the recently-pressed lump, and it is removed. The crank N is then turned back, the sides F F thereby closed, more tobacco introduced, the cover G closed and fastened, and the operation repeated. At the same time the operator at the left of the machine has pressed a lump every time the operator at the right has released and removed one, and vice versa.

Having thus described my invention, I wish to secure by Letters Patent and claim—

1. In a tobacco-pressing machine, the combination of the valve-levers *d d*, valve-rod *m*, and valve D, constructed and arranged substantially as described, and for the purpose

of alternately moving the followers H H and rams K K.

2. In a tobacco-pressing machine, the pressing-boxes C C, when constructed with the sliding sides F F and pivoted cover G, constructed and arranged substantially as described, 35 and for the purposes set forth:

3. In a tobacco-pressing machine, the crank N, eccentrics *n n*, rods *p p*, and studs *r r*, when used for opening and closing the sides F F, substantially as described.

4. In a tobacco-pressing machine, the combination of the steam-cylinder B, steam-chest E, valve D, valve-stem *m*, and valve-lever *d*, with the pressing-boxes C C, rams K K, and followers H H, all constructed and arranged substantially as described, and for the purposes set forth.

5. In a tobacco-pressing machine, the combination of the cranks N N, eccentrics *n n*, rods *p p*, and studs *r r*, with the pressing-boxes C C, constructed with sliding sides F F, pivoted cover G, catch-lever *g*, and catch *g'*, all arranged and operating as described, and for the purposes set forth.

AURELIUS W. MAHON.
